UNITED STATES PATENT OFFICE.

WILLIAM EDMUND O'REILLY, OF LONDON, ENGLAND.

SAFETY-RAZOR.

1,157,249.

Specification of Letters Patent.

Patented Oct. 19, 1915.

Application filed May 12, 1914. Serial No. 838,008.

To all whom it may concern:

Be it known that I, WILLIAM EDMUND O'REILLY, a subject of the King of Great Britain, residing in London, England, have 5 invented certain new and useful Improvements in Safety-Razors, of which the following is a specification.

This invention relates to an improved safety razor and it refers to razors of the kind in which the handle consists of a resilient member or members. As distinguished from other razors of the type just referred to, in which the handle-forming members have to be wholly or partly detached from the blade holder in order to be laid flat upon the latter for packing, the present invention has for its object to provide a razor having resilient handle forming members, which are so constructed and 15 arranged that they do not require to be detached from the blade holder for packing or when same is to be placed in its case. With this end in view, the said handle members are formed either integral with the blade 20 holder, or they are formed separate from the said blade holder and rigidly attached thereto in any convenient manner.

In the razor according to the present invention and in the preferred form, I employ a holder of the usual comblike configuration and to which holder the blade may be secured in any convenient manner. Formed integral with the blade holder and located one at each end, preferably in the 30 center thereof, are two extensions of suitable width and of such thickness that they are sufficiently resilient to permit them to be flexed to occupy the desired positions. The extensions are bent or turned inward, 35 and at their adjacent ends they are slotted or otherwise shaped so that the said ends may be connected or interlocked to render them sufficiently rigid to serve as a handle.

In order that the invention may be the better understood, drawings are appended in which:

Figure 1 is a plan of the razor showing the handle members in the position for use. Fig. 2 is a side view. Fig. 3 is an end view. 50 Fig. 4 is a longitudinal section of the guard to an enlarged scale, the handle members and blade being omitted.

Referring to the accompanying drawings *a* indicates the blade holding portion of the

razor having slots upon each edge so that it 55 presents the usual comblike guard common to razors of this type.

b indicates means for securing the blade *c* which blade is preferably of the double edged form and is provided with a longitudinal slot. While the method and means for attaching the blade to the holder may be varied as desired, in the present instance I have illustrated blade holding means such as forms the subject of English Letters Patent No. 4767 of 1913, and which comprises a longitudinal projection which is preferably of such height that when the razor is being stropped it maintains the blade at the correct angle to the strop for sharpening, 70 and which projection is slotted at each end at *b* as clearly shown in Fig. 4 so that the razor blade may be slipped thereunder by passing said projection through one end of the slot, sliding the blade longitudinally 75 until the opposite end of the projection may be passed through the slot when the blade is moved slightly backward until both ends of the projection overlap the blade.

Formed integral with the holder *a* and 80 disposed one at each end thereof are extensions *e* preferably of the outline shown, and which extensions are of such thickness, either locally or throughout their length, as to render them sufficiently resilient to be 85 flexed or bent without breaking.

The members *e* are turned or bent inward upon the top of the holder *a* and when not connected occupy a position approximately that shown in dotted lines *x* Fig. 3. The 90 handle members *e* are provided at their adjacent ends with a means of connection and in the present instance such means comprises slots *f* *f* which, when the handle members are drawn upward, or away from 95 the holder *a*, automatically engage and firmly connect the parts holding them in the position shown.

When it is desired to use the razor the parts *e* are pressed outward until their slotted ends automatically spring into engagement being retained in their engaged position by the pressure produced by the tendency of the parts *e* to return to their normal position. When not required for use 100 the parts *e* may, if necessary, be pressed inward toward the holder *a* until they are 105 close thereto when the razor occupies a mini-

mum of space and may be contained in a case of very small dimensions.

While I do not desire to limit myself in any way to the construction of the blade holder *a*, I may, if desired, form it of sufficiently thin metal to enable it to be flexed longitudinally as the handle members are brought together and thereby clamp the blade beneath the ends of the projection *b*.

10 Claims:

1. A safety razor comprising a blade, a guard, means for securing the blade to the guard, comprising a longitudinal projection upon the guard having a slot at each end 15 engaging the blade, flexible handle members formed integrally with the guard and normally disposed in a plane parallel with the plane of the guard, and means for connecting the handle members when in position 20 for use.
2. A safety razor comprising a blade, a guard capable of flexure in the direction of its length, a longitudinal projection on said guard having a slot at each end engaging 25 the blade, flexible handle members disposed one at each end of the guard and normally disposed in a plane parallel with the plane

of the guard and means for connecting the handle members when in position for use.

3. A safety razor comprising a blade, a guard capable of flexure in the direction of its length, a longitudinal projection on said guard having a slot at each end engaging the blade, flexible handle members disposed one at each end of the guard and normally 35 disposed in a plane parallel with the plane of the guard and means for connecting the handle members when in position for use.

4. A safety razor comprising a blade, a guard, means for securing the blade to the 40 guard, flexible handle members capable of being disposed in a plane parallel to the plane of the guard and permanently attached at one end to the guard and normally 45 having their opposite ends free, and means upon said free ends whereby they may be connected when required for use.

In witness whereof I have hereunto set my hand in the presence of the two undersigned witnesses.

WILLIAM EDMUND O'REILLY.
